Primary Examiner — George D. Kirschbaum*Assistant Examiner* — Antoinette M Suiter(74) *Attorney, Agent, or Firm* — Mestechkin Law Group P.C.(57) **CLAIM**

I claim the ornamental design for an automatic door opener, as shown.

DESCRIPTION

FIG. 1 is a front perspective view of an automatic door opener showing my new design;

FIG. 2 is a front isometric view thereof;

FIG. 3 is a rear view thereof;

FIG. 4 is a rear isometric view thereof;

FIG. 5 is a side view thereof;

FIG. 6 is a top view thereof;

FIG. 7 is a bottom view thereof;

FIG. 8 is a side view showing my new design; and,

FIG. 9 is a side view showing my new design in an alternate configuration thereof.

The broken lines are optional elements and therefore form no part of the claimed design.

1 Claim, 9 Drawing Sheets(56)
